J. F. CLASS

APPARATUS FOR APPLYING VAPORS TO A PATIENT

Original Filed April 28, 1921

UNITED STATES PATENT OFFICE.

JOHN F. CLASS, OF DAYTON, OHIO.

APPARATUS FOR APPLYING VAPORS TO A PATIENT.

Original application filed April 28, 1921, Serial No. 465,111. Divided and this application filed August 11, 1922. Serial No. 581,248.

This invention relates to an apparatus for applying vapors to the body of a patient and the apparatus here shown is designed more particularly for treating the head or 5 heads of one or more patients.

The present application is a division of the application for patent filed by me April 28, 1921, Serial No. 465,111.

One object of the invention is to provide 10 an apparatus of this kind by means of which a plurality of patients may be simultaneously treated.

A further object of the invention is to provide in connection with such an apparatus a cabinet adapted to apply vapors to the head of a patient.

A further object of the invention is to provide such an apparatus in which the head cabinet will be adjustable relatively 20 thereto.

Other objects of the invention will appear as the device is described in detail.

In the accompanying drawings Fig. 1 is a side elevation, partly broken away, showing 25 an apparatus embodying my invention; Fig. 2 is a top plan view of such an apparatus, with a part of the head cabinet broken away; Fig. 3 is a vertical sectional view of the cooling and distributing chamber forming 30 a part of the apparatus; Fig. 4 is a vertical sectional view taken through the head cabinet; and Fig. 5 is a bottom plan view of the head cabinet.

In these drawings I have illustrated one 35 embodiment of my invention and have shown the same as designed more particularly for treating the head, or heads, of one or more patients, but it will be understood that the apparatus may be used for various 40 purposes and that the head cabinets themselves may take various forms.

That form of the apparatus here illustrated comprises a casing 1 preferably formed of sheet metal and constituting a 45 vapor chamber which may be connected in any suitable manner, as by means of a conduit 2, with a suitable vapor generator such, for example, as that shown in the above mentioned application. The conduit 2 preferably extends slightly above the bottom wall of the casing so that products of condensation will not drain back into the conduit. The casing itself may be supported in any suitable manner, but as here

shown, it is provided with standards, or 55 legs, 3 by which it may be supported on the floor, or other suitable structure. Arranged about and preferably supported by the casing 1 are a plurality of devices for applying vapors to the human body, these devices being preferably adapted to apply the vapors to a selected portion of the body only and in the present instance I have shown each of these devices as comprising a head cabinet with which vapors may be applied to the head of a patient. Each such head cabinet comprises a casing 4 of a size and shape adapted to receive the head of a patient and having a bottom wall 5 provided with a recess 6 to receive the neck of 70 a patient to whose head the cabinet may be applied. The forward portion of the cabinet is provided with an opening through which the head of the patient may be inserted and this opening is closed by a hinged door, or closure, 7 having therein an opening 8 shaped to receive the face of the patient so that the mouth, nose and eyes will not be subjected to the action of the vapors. In order to form a tight joint between the face and the edge of the opening 8 I have provided the door with a series of projections, or hooks 9 about which a towel or other cloth may be supported in contact with the face of the patient. The 75 door 7 is provided at its lower edge with a flange 10 having a curved edge 11 to fit about the neck of a patient and which, together with the recess 6 in the bottom wall 5 of the cabinet, forms a snug closure about 80 the neck of the patient.

The cabinet may be supported on and connected with the casing 1 in any suitable manner, but I prefer that it should be vertically adjustable so as to accommodate it 95 to patients of different heights and I have, therefore, shown the same as having pivotally connected to each side thereof an arm 12. Arranged on each side of the cabinet is a pair of parallel links 13 each having one end pivotally connected with the lever 12 on the adjacent side of the cabinet and having its other end pivotally connected with the cabinet, preferably by means of a supporting bracket 14. By means of this 100 construction the head cabinet may be raised and lowered to the desired extent but because of the pivotal connection of the sup-

porting arms with the cabinet the cabinet may be maintained in the proper vertical position in all adjustments thereof.

There may be any suitable number of head cabinets arranged about the distributing chamber but in the present structure I have shown means for supporting four of such cabinets thereon. Each cabinet is connected with the distributing chamber by 10 means of a conduit 15 which is preferably flexible to permit it to accommodate itself to the adjustments of the cabinet. The conduits may lead into the casing or distributing chamber at any desired point and 15 I prefer that the casing be provided with reduced upper portion 16 with which the several conduits 15 are connected. The flow of the vapors through each conduit is controlled by a valve 17 which is preferably provided with a handle 18 which may, if desired, have connected therewith a cord 19 extending to a point adjacent to the patient so that the valve may be controlled by the patient.

20 While I have shown and described one embodiment of my invention I wish it to be understood that I do not desire to be limited to the details thereof as various modifications may occur to a person skilled in the art.

Having now fully described my invention what I claim as new and desire to secure by Letters Patent is:

30 1. In an apparatus of the character described, a vapor receptacle having means

for connecting the same with a vapor generator and comprising a vapor mixing and distributing chamber, a device for applying vapors to the body of a patient, a conduit connecting said vapor applying device with 40 said chamber, an arm pivotally mounted on said vapor applying device, and a pair of substantially parallel links each pivotally connected at one end with said arm and at 45 the other end with said receptacle.

2. In an apparatus of the character described, a vapor receptacle having means for connecting the same with a vapor generator and comprising a vapor mixing and distributing chamber, a head cabinet comprising 50 a casing mounted on said receptacle and having an opening in the bottom wall thereof, and a hinged door on the front wall thereof, said door having an opening 55 to receive the face of a patient whose head is within said cabinet, and means for connecting said cabinet with said receptacle.

3. A head cabinet comprising a casing having an opening in its front wall, and 60 an opening in its bottom wall, a door to close the opening in the front wall of said cabinet and having an opening for the face of the patient whose head is within said cabinet, said door also having a flange overlapping a portion of the opening in the 65 bottom wall of said cabinet.

In testimony whereof, I affix my signature hereto.

JOHN F. CLASS.
